(57) CLAIM

The ornamental design for the dumbbell shaped beverage bottle, as shown and described.

DESCRIPTION

FIG. 1 is a top, front and side perspective view of an ornamental design for a dumbbell shaped beverage bottle according to the present invention;

FIG. 2 is a front elevation view thereof; the left side, right side and rear elevation being identical thereto;

FIG. 3 is a top plan view thereof; and,

FIG. 4 is a bottom plan view thereof.

All portions shown in broken lines are environmental and illustrative only and form no part of the claimed design.
